Inventor:

Justine A. Fisher,
By her Attorney,
Leo P. Math

UNITED STATES PATENT OFFICE.

JUSTINE A. FISHER, OF NEW YORK, N. Y.

HAT-PROTECTOR.

1,397,246.

Specification of Letters Patent.

Patented Nov. 15, 1921.

Application filed October 22, 1920. Serial No. 418,858.

To all whom it may concern:

Be it known that I, JUSTINE A. FISHER, a citizen of the Republic of Czechoslovakia, having declared my intentions of becoming a 5 citizen of the United States, residing in the borough of Manhattan, city, county, and State of New York, have invented certain new and useful Improvements in Hat-Protectors, of which the following is a specification.

10 While applicable to hats generally my invention is designed more particularly for the protection of masculine stiff hats, and especially those made of straw,—the object being to provide a simple, cheap, light weight, strong, tenacious and effective cover for protection against the deleterious effects of rain or moisture, as well as for use as an envelop for storage or transportation.

15 I am aware that sheet rubber has been used in the manufacture of hat protectors, but unless the sheets are so thick and heavy as to render the protector cumbersome, such material is lacking in strength and tenacity, 20 and rips or tears if great care is not exercised in applying or detaching the protector from the head gear, besides which the relatively thin rubber is not impervious to moisture. Furthermore rubber sheeting 25 soon deteriorates in quality and becomes brittle and subject to crazing, rendering the covering useless as a protector for the purposes indicated.

30 My invention is designed to obviate these difficulties and to afford a strong, light weight, flexible, tenacious covering of durable quality which is absolutely impervious to moisture; and the invention consists in a 35 protector of the character designated made entirely of oiled silk, so called commercially, with the joints between the parts hermetically sealed by means of a waterproof cement, so as to constitute practically a unitary structure, as hereinafter more fully set forth.

40 In the accompanying drawings,

45 Figure 1, is a central cross section of a straw hat showing the practical application of my improved protector;

50 Fig. 2, is a sectional perspective upon a larger scale, broken away centrally, of my improved protector.

For convenience of illustration, in Fig. 1, the hat is shown in white outline and the

protector in solid black; but in Fig. 2, the 55 parts of the hat are hatched in one direction and the parts of the protector in the opposite direction, also for convenience of illustration.

It is to be understood that the thickness 60 of the oiled silk of which the protector is formed is necessarily exaggerated in the drawings. As a matter of fact it is exceptionally thin.

My protector is formed entirely of the 65 sheet material known commercially as "oiled silk"; and consists of the crown top *c*, side strip *s*, and rim section *r*, these parts, where they overlap, as at *a*, *a'*, being hermetically sealed and united permanently by means of 70 a moisture proof adhesive.

The rim section *r*, is also formed with a 75 peripheral overlap *r'*, the inturned edge *r''*, of which is in like manner hermetically sealed and united to the under side of the said rim section *r*, forming a circumscribing casing *h*, which incloses an elastic resilient piping or drawing cord *d*, by means of which the protector is stretched and held taut upon the hat when applied thereto.

80 *h*, represents the cross section of the hat body; *b*, the external hat band; and *i*, the internal sweat band.

85 By the term moisture-proof adhesive as herein used I mean to include any binding material adapted to make a permanent, moisture proof, joint between the opposed surfaces of oiled silk to which it is applied.

90 The oiled silk is strong, tough and tenacious, and absolutely impervious to moisture; and the several sections of the protector being united, and the joints permanently sealed by a moisture proof adhesive as stated, the product, as a unitary structure, is substantial and durable, and practically 95 indestructible if used with ordinary care.

Furthermore it is of light weight, and neat and compact in appearance as applied to a hat,—the joints being inconspicuous.

What I claim as my invention and desire 100 to secure by Letters Patent is,

As an article of manufacture, a hat protector of the character designated, comprising a top crown piece of flexible oiled silk formed with a peripherally inturned flange, 105 a side-crown band of oiled silk hermetically cemented at its upper edge to the said peripheral crown flange, and a rim section of

oiled silk formed with a flange hermetically cemented to the lower edge of said side crown band, the peripheral edge of said rim section being inturned to embrace the rim of 5 a hat, and being formed with an edge piping containing an elastic resilient contractive cord, and the whole protector being col- lapsible and foldable upon itself, substantially in the manner and for the purpose described.

JUSTINE A. FISHER.
